Fig. 8.

Figure 10 is a circular diagram. It features a central point with a small circle around it. A vertical line passes through the center, and a horizontal line passes through the center, intersecting at the central point. From the center, several radial lines extend outwards. Some of these radial lines are labeled with numbers: '4' at the top right, '9a' at the top left, '5' at the bottom left, and '7' at the bottom right. There are also other unlabeled radial lines.

UNITED STATES PATENT OFFICE.

OSCAR I. STRAUB, OF THE UNITED STATES ARMY.

PROJECTILE.

1,312,765.

Specification of Letters Patent. Patented Aug. 12, 1919.

Application filed December 26, 1917. Serial No. 208,873.

To all whom it may concern:

Be it known that I, OSCAR I. STRAUB, colonel C. A. C., U. S. A., a citizen of the United States, stationed at Fort Adams, Newport, in the county of Newport and State of Rhode Island, have invented certain new and useful Improvements in Projectiles; and I do hereby declare the following to be a full, clear, and exact description of the invention, such as will enable others skilled in the art to which it appertains to make and use the same.

My present invention relates to improvements in projectiles to be used in the manner 15 of the well known chain shot.

According to my invention I use a projectile provided with a spool on which one or more coils of wire or chain are wound. These coils of wire or chain are wound on 20 said spool in reverse directions from the central portion of the wire or chain, so that after the spool is discharged from the gun and is given a rotary motion, caused by the rifling of the gun, the free ends of the wire 25 will unwind in reverse directions from the spool, leaving the spool to continue on its flight.

Instead of a single wire or chain wound on the spool, I may have a plurality of said 30 wires or chains. I may have the wire or chain fly out centrifugally of its own weight, or I may supplement this centrifugal action by attaching metal bars or weights to the free ends of the wire or chain, the wire or 35 chain serving as a bridle connecting the two bars or weights.

While either a wire or chain may be used in the apparatus hereinafter described, I prefer to use the wire because it may be 40 more compactly wound on the spool, and thus a greater weight may be carried within the dimensions of the projectile, thus permitting greater extension when uncoiled.

For convenience of reference in the following specification and claims, I shall herein-after use the term "wire," with the understanding that this term is intended to cover either a wire or a chain.

My invention will be more fully understood by reference to the accompanying drawings, in which similar parts are indicated by similar reference symbols throughout the several views, and in which:

Figure 1 is a side elevation of one form of 55 the invention, in which the detachable cap

as adapted for use at short ranges, which may be used with a fuse for longer ranges is omitted, but is indicated in dotted lines.

Fig. 2 shows a plan view of the device shown in Fig. 1, with the detachable cap 60 shown in dotted lines removed.

Fig. 3 is a diagram showing the mode of winding the wire on the spool, the wire and the spool being shown in elevation, and the other parts shown in central vertical section 65 along the line 3-3 of Fig. 2, and looking in the direction of the arrows.

Fig. 4 shows a section along the line 4-4 of Fig. 3, the wire being shown diagrammatically.

Fig. 5 shows the wire and the bars attached to the ends thereof, after the wire has left the spool and the wire has been extended.

Fig. 6 is a similar view to Fig. 3, but shows 75 the projectile to be used like cannister, the wire being also shown diagrammatically.

Fig. 7 shows a section along the line 7-7 of Fig. 6, and looking down, the wire being shown in the proper relation.

Fig. 8 shows a form of the invention in which three coils of wire are used, the wire being shown diagrammatically, to illustrate the winding, and in which form the cap and base of the projectile are blown off by bursting charges, the view being partly in section 85 along the line 8-8 of Fig. 9.

Fig. 9 is a plan view of the device shown in Fig. 8, with the cap of the projectile removed, the wire being shown in the proper 90 relation.

Fig. 10 is a similar view to Fig. 9, but shows a projectile provided with only two coils of wire.

Fig. 11 shows a similar projectile mainly 95 in central vertical section, illustrating the device as applied to a modified form of shrapnel; and

Figs. 12 and 13 show cross sections of wire specially suitable for use with the invention. 100

The invention herein described, is a further development of the invention disclosed in my pending application, filed October 5, 1917, Serial No. 194,952, and entitled Improvements in anti-aircraft projectiles.

Referring first to Figs. 1 to 5, which show a simple form of the invention, 1 represents the central spindle of the spool, on which spindle the disks 2 and 3 are mounted, around which spindle and between which 110

disks the wire 4 is coiled compactly, as shown in Fig. 1 and as diagrammatically shown in Fig. 2.

- Spanning the disks 2 and 3 are the bars 5, which bars are detachably connected to said disks 2 and 3, to which bars are connected the ends 4^a of the wires. These wires are shown in Figs. 1 to 4 of a single length, each length composed of two coils 4^a and 4^b (shown diagrammatically in Fig. 3) wound in reverse directions and connected together by the loop 4^c, the free ends 4^d being secured in any suitable way to the bars 5. In order to provide suitable strength to withstand the shock of discharge when the projectile is fired from the gun, the disk 2 is reinforced by a suitable base piece 6, carrying the rotation band 7, adapted to engage the rifling of the gun, from which the projectile is fired.
- This base piece 6 is provided with a socket 6^a to receive the lower ends of the bars 5, the upper ends of the bars projecting into a corresponding socket 8^a in the cap 8 of the projectile carrying the fuse, when such cap is used.

This cap 8 is shown in dotted lines in Figs. 1 and 3, and in full lines in Fig. 8, but where it is desired to use the projectile at very short range this cap is removed, the parts then being in the position as shown in full lines in Figs. 1 and 3.

In order to provide for the use of the projectile at close range, and without the cap, it will be desirable to temporarily secure the bars 5 to the disks 2 and 3, which may be done by tying the same with combustible flexible fastening means, such as the fusible wire 9 and 9^a. Instead of the fusible wire some combustible connection may be used, such as catgut, strong cord, or the like, which is consumed by the powder gases when the projectile is fired from the gun.

After the projectile is fired, the centrifugal force imparted to the spool will cause the wire wound thereon to unwind in reverse directions at the same time the bars 5 will be thrown out by centrifugal force, and the bars and wire will assume the position shown in Fig. 5, and flying forward would injure the lighter parts of aeroplanes, such as the stays or the like, and would also tend to be caught in the propellers of the aeroplane, thus seriously injuring the aircraft.

If it is desired to use the projectile at longer range, a time fuse arrangement may be used, such as is shown in Fig. 8, which will be hereinafter described.

Referring now to Figs. 6 and 7, which show the wire diagrammatically, this construction is generally similar to that shown in Figs. 1 to 4, except that the spool is inclosed in a cylindrical shell 11, of thin metal, and the base piece 6 and the disk 2 are perforated, as at 12, to permit the powder gases to enter into the hollow portion of

the cylinder 11, and blow the thin metal casing from the spool, and thus unmasking the wire when or shortly after the spool leaves the gun.

The ends 4^e of the wire in this case are free, not being attached to any bars or weights, and in this case, of course, the wire should be sufficiently heavy to be thrown out by its own inertia under the action of centrifugal force imparted by the rifling of the gun.

As before stated, in place of wire, coils of chain may be used, but I prefer to use wire on account of the fact that greater density of metal can be inclosed in the casing 11 if wire be used than if chain be used.

For the sake of clearness in the drawings, I have shown the wire diagrammatically in Figs. 6 and 7, but, of course, the wire should be wound compactly as shown in Figs. 1 and 2. In order to secure more compact winding, the wire should preferably be either rectangular, or have its cross section in the form of an equilateral triangle, as shown, respectively, in Figs. 12 and 13.

Not only do we secure greater metal density for the projectile by having the wire in such cross section, but the wire is provided with cutting edges which tend to cut any object which it strikes at high velocity, whether the velocity be that of the wire or that of the target.

It will be obvious that wire having its cross section in the form of a rectangular, or in the form of an equilateral triangle, can be wound into a compact mass on the spool.

Referring now to Figs. 8 and 9, Fig. 8 shows a central vertical section through the projectile, the wire, spindle and fuse being shown in elevation and the other parts in section. In this case there are three coils of wire, separated by washers 10, the ends of each coil of wire being connected to a corresponding pair of bars 5, so that after the projectile is fired and the bars released, there will be three sets of bars and wires thrown out by centrifugal force.

The ends of the bars 5 are preferably secured in the sockets in the base piece 6 and cap 8, and in order to release the bars and wires when desired, the cap 8 is blown off at a predetermined time and range by means of the powder charge 13 contained in the cap and ignited by the time fuse 14.

The spindle 1 is hollow and filled with powder, and carries the flame, through the channel 6^b, to the bursting charge 15 in the base piece 6. The explosion of the powder charge 13 will blow the cap off, thus releasing the bars 5, and then the powder charge 15 will blow the disk 2 loose, permitting the bars to be thrown outward and the coils to uncoil and spread out in the position shown in Fig. 5. While the wire is shown coiled diagrammatically in Fig. 8, it would, of

course, be coiled in the compact form so as to get the density of metal in the projectile, as shown in Fig. 9.

If it be desired to use the projectile shown in Fig. 8 at very short range, the cap 8 may be removed, in which event, in order to hold the forward ends of the bars together until the projectile leaves the gun, the opposite bars are connected by the fusible wires 9, or 10 other combustible connection, such as cat-gut, or the like, already described in connection with Figs. 1 to 4.

It will only be necessary to hold together the upper ends of the bars, for the lower 15 ends will be held temporarily in their sockets in the base piece 6, but after the projectile leaves the gun the bars will tend to fly outward under the action of centrifugal force, and when their upper ends are freed, 20 will become disengaged from the base piece, which will be pressed backward by the resistance of the air, and the bars will fly outward together with the coils of wire, each coil with its corresponding pair of bars 25 finally assuming the position, shown in Fig. 5.

In Figs. 8 and 9, I have shown three coils of wire with six bars, while in Fig. 10 I have shown two bars only which, of course, would 30 be connected together by two coils of wire only, each coil of wire being coiled in reverse directions, as fully described with reference to Figs. 3 and 6.

Referring now to Fig. 11, which shows 35 the idea as applied to a modified form of shrapnel, and in which the wire is also shown diagrammatically as a single coil wound in reverse directions on the spool, 8 represents the cap of the projectile similar 40 to that shown in Fig. 8, and having a time fuse 14 similar to that shown in Fig. 8. This cap 8 and the base piece 6 are both screwed to the cylindrical shell 16 of the shrapnel, and the spindle 1 is hollow and transmits the 45 flame from the bursting charge in the cap 8 to the bursting charge 17 in the base piece 6.

When the bursting charge 13 in the cap 8 explodes, it will blow the cap off, and the bursting charge 17 will tend to throw the 50 spool forward whether the shell 16 bursts or not, and this will cause the wire to be projected forward at a greater velocity than it already has, especially if the shell 16 does not burst.

55 The ends 4^a of the wire in this case are shown as free, and the wire should be of sufficient mass to act as an effective projectile.

As previously stated, chain may be used in place of wire, if desired, but I prefer to 60 use wire for reasons already stated.

It will thus be seen that in Figs. 1 to 4, I provide a projectile which may be used either at very close range, or if the fuse cap be applied may be used at any desired range 65 within the power of the gun; while in Fig. 6

the device is shown as capable of use at very short ranges only, like cannister.

In Fig. 8, the projectile more strictly corresponds to the modern shot having a low bursting charge; while in Fig. 11 the device 70 is somewhat similar to shrapnel.

It will be obvious that if the wire be straight and wound on the spool, it will tend to unwind due to its own resiliency, and this will supplement the action of the centrifugal force in unwinding the wire when it is released from the spool. 75

By having the wire tempered and hardened, not only will this resiliency be increased, but the wire will also be more effective as a cutting implement when striking the target. Thus the wire will be drawn along the target, the angular edges cutting like a saw. 80

It will be noted that in each case the 85 free ends of the wire are held in position until ready to be released from the spool, either by means of the bars 5 to which they are attached as shown in Figs. 1 to 5 and 8 to 10, or the free ends of the wire are held 90 by the containing shell as shown in Figs. 6, 7 and 11.

The projectile is especially adapted for use at very close range, against aeroplanes, or other aircraft, and is also especially 95 adapted at very close range for use against the periscopes of submarines, and also against wire entanglements. It may obviously be used at longer ranges by the use of a suitable time fuse, operating a bursting 100 charge for the projectile.

While I have shown a single length of wire in Figs. 1 to 4, Fig. 6, and Fig. 11, two lengths of wire in Fig. 10 and three lengths of wire in Figs. 8 and 9, it will be obvious 105 that the number of lengths of wire or chain may be varied to suit the size of the projectile, the cross section of the wire or chain used, and other conditions, and I do not mean to limit myself to any particular number of coils of wire or chain. 110

It will be obvious that the bars 5 may extend over a considerable arc of the cylindrical surface of the mass of wire mounted between said bars and the axis of the spool; 115 thus securing greater weight and strength and forming a more complete retainer for the wire coils.

It will be obvious also that various other changes might be made in the construction, 120 combination and arrangement of parts which could be used without departing from the spirit of my invention, and I do not mean to limit the invention to such details except as particularly pointed out in the 125 claims.

Having thus described my invention, what I claim and desire to secure by Letters Patent of the United States is:

1. A projectile comprising a base member 130

- and a cap, with a spindle connecting the two, thus constituting a spool, means for imparting a rotary motion to said spool about the axis of said spindle, and a coil of wire wound from the end of said spool in one direction toward the center of said spool, and then in reversed direction toward the opposite end of said spool.
2. A projectile comprising a base member and a cap, with a spindle connecting the two, thus constituting a spool, means for imparting a rotary motion to said spool about the axis of said spindle, and a coil of wire wound from the end of said spool in one direction toward the center of said spool, and then in reversed direction toward the opposite end of said spool, with a pair of bars detachably connected to said cap and base member, and secured respectively to the free ends of said wire.
3. A projectile comprising a base member and a cap, with a spindle connecting the two, thus constituting a spool, means for imparting a rotary motion to said spool about the axis of said spindle, and a coil of wire rectangular in cross section and having its two ends wound closely from the end of said spool in one direction toward the center of said spool, and then in reversed direction toward the opposite end of said spool.
4. A projectile comprising a base member and a cap, with a spindle connecting the two, thus constituting a spool means for imparting a rotary motion to said spool about the axis of said spindle, and a coil of wire rectangular in cross section and having its two ends wound closely from the end of said spool in one direction toward the center of said spool, and then in reversed direction toward the opposite end of said spool, with a pair of bars detachably connected to said cap and base member, and secured respectively to the fore ends of said wire.
5. A projectile comprising a base member and a cap, with a spindle connecting the two, thus constituting a spool, means for imparting a rotary motion to said spool about the axis of said spindle, and a plurality of coils of wire each coil wound from the end of said spool in one direction toward the center of said spool, and then in reversed direction toward the opposite end of said spool.
6. A projectile comprising a base member and a cap, with a spindle connecting the two, thus constituting a spool, means for imparting a rotary motion to said spool about the axis of said spindle, and a plurality of coils of wire each coil wound from the end of said spool in one direction toward the center of said spool, and then in reversed direction toward the opposite end of said spool, with pairs of bars detachably connected to said cap and base member, and secured respectively to the free ends of said wire.
7. A projectile comprising a base member and a cap, with a spindle connecting the two, thus constituting a spool, means for imparting a rotary motion to said spool about the axis of said spindle, and a plurality of coils of wire rectangular in cross section and each coil having its two ends wound closely from the end of said spool in one direction toward the center of said spool, and then in reversed direction toward the opposite end of said spool.
8. A projectile comprising a base member and a cap, with a spindle connecting the two, thus constituting a spool, means for imparting a rotary motion to said spool about the axis of said spindle, and a plurality of coils of wire rectangular in cross section and each coil having its two ends wound closely from the end of said spool in one direction toward the center of said spool, and then in reversed direction toward the opposite end of said spool, with pairs of bars detachably connected to said cap and base member, and secured respectively to the free ends of said coils of wire.
9. A projectile comprising a base member and a cap, with a spindle connecting the two, thus constituting a spool, means for imparting a rotary motion to said spool about the axis of said spindle, and a coil of wire wound from the end of said spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.
10. A projectile comprising a base member and a cap, with a spindle connecting the two, thus constituting a spool, means for imparting a rotary motion to said spool about the axis of said spindle, and a coil of wire wound from the end of said spool in one direction toward the center of said spool, and then in reversed direction toward the opposite end of said spool, with a pair of bars detachably connected to said cap and base member, and secured respectively to the free ends of said wire, with means operated by the explosion of the propelling charge of the gun for releasing the free ends of said wire and causing it to unwind from said spool under the action of centrifugal force.
11. A projectile comprising a base member and a cap, with a spindle connecting the two, thus constituting a spool, means for imparting a rotary motion to said spool about the axis of said spindle, and a coil of wire rectangular in cross section and having its two ends wound closely from the end of said

- spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.
12. A projectile comprising a base member and a cap, with a spindle connecting the two, thus constituting a spool, means for imparting a rotary motion to said spool about the axis of said spindle, and a coil of wire rectangular in cross section and having its two ends wound closely from the end of said spool in one direction toward the center of said spool, and then in reversed direction toward the opposite end of said spool, with a pair of bars detachably connected to said cap and base member, and secured respectively to the free ends of said wire, with means operated by the explosion of the propelling charge of the gun for releasing the free ends of said wire and causing it to unwind from said spool under the action of centrifugal force.
13. A projectile comprising a base member and a cap, with a spindle connecting the two, thus constituting a spool, means for imparting a rotary motion to said spool about the axis of said spindle, and a plurality of coils of wire each coil wound from the end of said spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.
14. A projectile comprising a base member and a cap, with a spindle connecting the two, thus constituting a spool, means for imparting a rotary motion to said spool about the axis of said spindle, and a plurality of coils of wire each coil wound from the end of said spool in one direction toward the center of said spool, and then in reversed direction toward the opposite end of said spool, with pairs of bars detachably connected to said cap and base member, and secured respectively to the free ends of said coils of wire, with means operated by the explosion of the propelling charge of the gun for releasing the free ends of said wire and causing it to unwind from said spool under the action of centrifugal force.
15. A projectile comprising a base member and a cap, with a spindle connecting the two, thus constituting a spool, means for imparting a rotary motion to said spool about the axis of said spindle, and a coil of wire rectangular in cross section and each coil having its two ends wound closely from the end of said spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.
16. A projectile comprising a base member and a cap, with a spindle connecting the two, thus constituting a spool, means for imparting a rotary motion to said spool about the axis of said spindle, and a plurality of coils of wire rectangular in cross section and each coil having its two ends wound closely from the end of said spool in one direction toward the center of said spool, and then in reversed direction toward the opposite end of said spool, with pairs of bars detachably connected to said cap and base member, and secured respectively to the free ends of said coils of wire, with means operated by the explosion of the propelling charge of the gun for releasing the free ends of said wire and causing it to unwind from said spool under the action of centrifugal force.
17. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool.
18. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool, with a pair of bars detachably connected to said cap and base member, and secured respectively to the free ends of said wire.
19. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire rectangular in cross section and having its two ends wound closely from the end of said spool in one direction toward the cen-

ter of said spool, and then in reversed direction toward the opposite end of said spool.

20. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire rectangular in cross section and having its two ends wound closely from the end of said spool in one direction toward the center of said spool, and then in reversed direction toward the opposite end of said spool, with a pair of bars detachably connected to said cap and base member, and secured respectively to the free ends of said wire.
- 20 21. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.

22. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool, with a pair of bars detachably connected to said cap and base member, and secured respectively to the free ends of said wire, with means operated by the explosion of the propelling charge of the gun for releasing the free ends of said wire and causing it to unwind from said spool under the action of centrifugal force.

23. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire rectangular in cross section and hav-

ing its two ends wound closely from the end of said spool in one direction toward the center of said spool, and then in reversed direction toward the opposite end of said spool, with means operated by the explosion of the propelling charge of the gun for releasing the free ends of said wire and causing it to unwind from said spool under the action of centrifugal force.

24. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire rectangular in cross section and having its two ends wound closely from the end of said spool in one direction toward the center of said spool, and then in reversed direction toward the opposite end of said spool, with a pair of bars detachably connected to said cap and base member, and secured respectively to the free ends of said wire, with means operated by the explosion of the propelling charge of the gun for releasing the free ends of said wire and causing it to unwind from said spool under the action of centrifugal force.

25. A projectile comprising a base member and a cap, with a spindle connecting the two, thus constituting a spool, means for imparting a rotary motion to said spool about the axis of said spindle, and a coil of wire angular in cross section wound from the end of said spool in one direction toward the center of said spool, and then in reversed direction toward the opposite end of said spool.

26. A projectile comprising a base member and a cap, with a spindle connecting the two, thus constituting a spool, means for imparting a rotary motion to said spool about the axis of said spindle, and a coil of wire angular in cross section wound from the end of said spool in one direction toward the center of said spool, and then in reversed direction toward the opposite end of said spool, with a pair of bars detachably connected to said cap and base member, and secured respectively to the free ends of said wire.

27. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool, and a fuse and powder charge

for releasing the free ends of said wire and causing it to unwind from said spool under the action of centrifugal force.

28. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire wound from the end of said spool in one direction toward the center of said spool, and then in reversed direction toward the opposite end of said spool, with a pair of bars detachably connected to said cap and base member, and secured respectively to the free ends of said wire, and a fuse and powder charge for releasing the free ends of said wire and causing it to unwind from said spool under the action of centrifugal force.

29. A projectile comprising a base member and a cap, with a spindle connecting the two, thus constituting a spool, a base piece connected to said spool adapted to withstand the shock of discharge, a soft metal rifling band carried by said spool for imparting a rotary motion to said spool about the axis of said spindle, and a coil of wire angular in cross section and having its two ends wound closely from the end of said spool in one direction toward the center of said spool, and then in reversed direction toward the opposite end of said spool, with a pair of bars detachably connected to said cap and base member, and secured respectively to the free ends of said wire, and a fuse and powder charge for releasing the free ends of said wire and causing it to unwind from said spool under the action of centrifugal force.

In testimony whereof I affix my signature.
OSCAR I. STRAUB.
